LAUNDRY WORK UNIT

John D. Morgan, Summit, N. J., and Hobart N. Durham, Jackson Heights, N. Y., assignors to Southern Brighton Mills, Atlanta, Ga., a corporation of Georgia

Application March 16, 1931. Serial No. 522,944

5 Claims. (Cl. 24—30.5)

The invention relates to new and useful improvements in laundry bag manufacturing and work units, and more particularly to improvements in bag closures especially adapted for use with netted laundry bags, but having other applications as well.

The invention consists in the novel parts, constructions, arrangements, combinations and improvements herein shown and described.

10 The accompanying drawings, referred to herein and constituting a part hereof, show illustrative embodiments of the invention, and together with the description, serve to explain the principles of the invention.

15 Of the drawings:—

Fig. 1 is a fragmentary elevation of a laundry bag and one form of closure embodying the invention;

20 Fig. 2 is a section taken on line 2—2 of Fig. 1; Fig. 3 is a detached perspective of one form of the closure tensioning and fastening device;

Fig. 4 is a fragmentary elevation of an open bag and a modified form of closure embodying the invention;

25 Fig. 5 corresponds to Fig. 4 but shows the bag in closed position;

Fig. 6 is a detached perspective view of a modified form of the closure tensioning and holding device;

30 Fig. 7 is a top plan corresponding to Fig. 6, but showing a further modification of the invention; and

Fig. 8 is a detached view of a locking device.

The invention in certain of its aspects is in 35 the nature of an improvement upon that of application Ser. No. 516,603 of Julian K. Morrison, filed February 18, 1931, but in other of its aspects it is otherwise applicable and useful.

The present invention is directed to providing 40 a bag closure which is very simple and strong, having few parts, and those of sturdy and inexpensive construction; the closure being firmly, easily and inexpensively attached to the bag, and being operable to close the bag by simple

45 movements, permitting the use of a free arm pull; the tightly constricted closure being practically automatically caught and held in the bag constricting position as the closure is tightened. The invention provides a single holding or

50 locking device, attached to a constricting bag closure, and apertured to receive and hold the closure for pulling it tight, preferably by a full arm reverse pulling movement, and having means, preferably integral, positioned to practically 55 automatically hold and lock the fully tensed bag

closing member, without further movement or manipulation by the operative.

The invention further provides a bag closure attached to the finished edge of the open end of the bag during the overcasting or other finishing 60 of the end, and as so attached being held or presented in proper distance within the open bag end to be passed about and to constrict and close it.

Referring now by way of example to the embodiment of the invention illustrated in the accompanying drawings, and for the present to the form of embodiment shown in Figs. 1 to 3, a bag 1 is shown, which for laundry work will be of the open netted, or leno weave indicated at 2 in 70 Fig. 1, although the invention is applicable to bags made from other fabrics. The embodied form of constricting closure 6 is preferably of a flat or tape-like form. For the purpose of providing a unitary manufacturing and laundry 75 work unit, the closure is attached to the relatively bulky, overcast, or otherwise finished edge 3 of the mouth of the bag. This provides a firm anchorage for the closure, and permits it to be attached during the finishing of the bag edge, 80 thereby obviating the labor and expense of a separate closure attaching operation. It is further designed to attach the closure so that it will be in the desired position preparatory to the bag-closing operation. Accordingly, a short tape-like 85 extension 9 is fixed to the member 6 in a suitable manner, as by means of a rivet 10, and the other end of the member 9 is turned into the edge 3 of the bag previous to its being overcast or otherwise finished and is sewn in therewith. Thus, 90 the closure is fixed to the bag in an exceedingly secure manner, and without requiring a separate or additional operation, and the closure is automatically positioned at the proper distance within the bag edge to form the constricting closure 95 of the bag.

In the embodied form of means for constricting and holding the closed bag, the member 6 is passed through a receiving and holding device 11 and drawn backwardly, and when in the fully 100 tensed position, the closure is practically automatically held against slipping or release. That is, the direction of the closing pull, without other movement or attention engages the tensed closure with the holding or detent means. In the embodied form of said means, a flat metal or other rigid member 11 has an internal aperture 12, and it is fastened to one end of the closure or tape 6. One end of the tape 6 is passed through the aperture 12 and turned back around the nar- 110

row back part 13 of the holder 11, and the end is then fastened to the tape separately or by the rivet 10. The tape 6 is provided with one or more apertures or eyelets 14, and the holder 11 has a projecting detent 15 having an elongated internal aperture 16, the projection or detent 15 preferably extending upwardly at an angle from the front side of the holder 11.

The closure as already described is in proper position for closing the bag, and the tip 17 of the tape 6 is passed through the opening 12 of the holder 11, and may be grasped within the fist and by a powerful arm movement may be pulled backwardly over the detent 15 until the open end 15 of the bag is drawn tight within the tape 6, and practically automatically, due to the direction of pull, an aperture or eyelet 14 will slip over the detent 15, and the bag is firmly held or locked in closed position by the tape 6, which is tight 20 about the mouth of the bag. This in itself constitutes a very secure holding or locking of the bag. If it is desired to further lock the bag, as, for instance, in laundry work, to absolutely insure against the bag, while being tumbled in the 25 washer, opening and losing the garments into the washer, a locking device may be passed through the aperture 16 above the tape 6, thereby absolutely locking the bag in closed position. As shown, a spring hook 19 is snapped through 30 the opening 16. The hook 19 may have attached thereto, or integral therewith, an identifying tag 20, having thereon the laundry number of the customer. There will be a sufficient number of the hooks 19 having the same customer's number 35 as there are classifications for the garments and articles usually sent to the laundry. Thus, after washing, all the garments and articles belonging to the same customer in separate bags, as classified, are reassembled by means of the identifying 40 tags, in accordance with modern laundry practice.

The present preferred commercial form of the invention is shown in Figs. 4 to 6 of the drawings. In said form, the holder, corresponding to the device 11 of the preceding figures, is made of fairly 45 heavy, stiff wire as shown at 24, the wire being bent to provide an aperture 25 corresponding to the aperture 12, and at the middle of the front end the wire is twisted into a loop 26, which is 50 forwardly inclined and is disposed perpendicularly to the plane of the holder itself. The openings in the tape 6 are preferably in the form of longitudinally-disposed openings, similar to a buttonhole, of a length just sufficient to pass over the loop 26, and the loop is of a size just large 55 enough to take the locking spring-hook 19. To resist the wear and tear, and especially the heavy pull at the rear end of the opening or buttonhole 27, the rear end is suitably reinforced, and this 60 is preferably done by weaving in as a filler thread

just at the rear end of the buttonhole a wire 29 or like resistant device. This device operates in the same way as that previously disclosed, but with the narrow longitudinally-disposed opening, or buttonhole, the fabric of the tape 6 is very much stronger than with the larger, transversely-disposed opening, and the entire strain is taken up on the reinforced rear end of the buttonhole 27. Furthermore, with the form of detent and aperture described, when the tape is pulled backwardly to bag constricting position, the detent and buttonhole automatically align, and pass into holding engagement without special care or attention on the part of the operator.

The invention in its broader aspects is not limited to the specific mechanisms shown and described but departures may be made therefrom within the scope of the accompanying claims without departing from the principles of the invention and without sacrificing its chief advantages.

What we claim is:—

1. As a manufacturing and laundry work unit, a bag of fabric, a constricting closure for the gathered bag end, and means apertured to receive the closure to permit it to be drawn tightly about the bag and a projection on said means to engage the tightly drawn closure and lock it in tightly drawn constricting position and a locking device therefor.

2. As a manufacturing and laundry work unit, a laundry bag, an apertured constricting closure for the bag, and means apertured to receive the closure to permit it to be drawn tightly about the bag and having an apertured projection adapted to project through an aperture in the tightly drawn closure and hold it in constricting position and a locking device engaging the apertured projection.

3. A holding device for a flexible bag closure comprising a member apertured to receive the closure and hold it against constricting tension and a fixed detent on said member adapted to engage and hold the tensed closure by projection through an aperture in the closure.

4. A holding device for a flexible bag closure comprising a member apertured to receive the closure and hold it against constricting tension and a detent projecting forwardly and upwardly from the body of said member and adapted to engage and hold the tensed closure.

5. A holding device for a flexible bag closure comprising a member apertured to receive the closure and hold it against constricting tension and a detent projecting forwardly and upwardly from the body of said member and adapted to engage and hold the tensed closure, said detent being apertured to receive a locking device.

JOHN D. MORGAN.
